United States Patent Office

Des. 182,177
Patented Feb. 25, 1958

182,177

DECK CHAIR OR SIMILAR ARTICLE

Sanford S. Golden, West Los Angeles, Calif.

Application July 5, 1957, Serial No. 46,836

Term of patent 14 years

(Cl. D15—11)

Fig. 1.

Fig. 2.

Fig. 3.

Fig. 1 is a perspective view of a deck chair showing my new design, the deck chair being viewed from the left side and front;

Fig. 2 is another perspective view thereof, the deck chair being viewed from the right side and front and being in a downwardly inclined position; and

Fig. 3 is a rear elevational view, on reduced scale, of the deck chair.

I claim:

The ornamental design for a deck chair or similar article, substantially as shown.
